UNITED STATES PATENT OFFICE.

THEODORE R. TREIBER, OF CHICAGO, ILLINOIS, ASSIGNOR TO WILLIAM H. McWHORTER, OF CHICAGO, ILLINOIS.

BOWLING ALLEY.

Application filed April 30, 1927. Serial No. 187,744.

My invention has for its main objects the provision of a bowling alley which is variably adjustable for leveling the bed of the alley, and which is constructed largely of metal, all with a view toward providing an alley of good playing qualities, economy in manufacture, ease of erection, solidity, comparatively great amount of salvage for re-erection after taking it down, and leveling without extensive planing, of the upper or playing surface of the bed.

With these objects in view my invention consists in certain features of novelty in the construction, combination, and arrangement of parts by which said objects and certain other objects hereinafter appearing, are effected, all as fully described with reference to the accompanying drawings and more particularly pointed out in the appended claims.

In the said drawings—

Figure 1 is a condensed cross section of a bowling alley embodying my invention, certain detail parts being omitted therefrom.

Figure 2 is an enlarged partial and condensed cross section of the same showing the parts in detail.

Figure 3 is a longitudinal vertical section of the same.

Figure 4 is a partial view taken on the line 4—4 of Figure 2 and with the bed removed.

Figure 5 is a condensed partial side elevation of the same.

Like characters of reference indicate like parts in the several views.

Referring to the drawings 1 designates a bowling alley bed and which is constructed of suitable material such as wood, which as shown and as usual consists of sleepers disposed in vertical planes and tongued and grooved and nailed together. See Figures 1 and 2.

The bed is carried on a carriage, preferably metal, which is constructed as follows. A pair of parallel metal right angle members 2 extend longitudinally of the bed and carriage and have legs thereof disposed inwardly and projecting downwardly while the other legs thereof consequently are disposed horizontally and project outwardly from the first mentioned legs. These angle members form the side portions of the carriage and metal angle members 3, forming cross ties, extend between the angle members

2 at intervals therealong and are secured to the angle members 2 by means of suitable metal brackets 4, the angle members 3 being disposed with the legs thereof respectively horizontal and vertical and having the upper surfaces of the horizontal legs thereof disposed in the same plane as the upper surface of the horizontal legs of the angle members 2 to form a suitable support surface for the bed 1. See Figures 1, 2, and 4. Metal right angle members 5 extend longitudinally of the carriage and have legs thereof secured downwardly on respective of the horizontal legs of the angle members 2 adjacent the outer edges thereof and have legs thereof disposed inwardly and projecting upwardly for transversely retaining the bed 1 on the carriage.

The carriage is supported on a base which is constructed as follows. A pair of parallel metal right angle members 6 extend longitudinally of the bed and carriage and have legs thereof disposed inwardly and projecting upwardly in overlapping relation with the downwardly projecting legs of the angle members 2. See Figures 1, 2, 3, and 5. Metal cross tie members 7 of inverted U-shape underlie the angle members 6 at intervals therealong and are secured therewith, and a pair of parallel metal inverted U-shaped members 8 extend longitudinally of the carriage and base and underlie the members 7 and are secured therewith, and these members 8 rest on and are secured with a foundation or floor 9 of the building where the installation is made, the members 7 and 8 or the member 8 alone being omitted where the foundation or floor 9 is suitable.

The carriage is supported on the base for vertical adjustment variable throughout its extent in the following manner. See Figures 2 and 5. Disposed at intervals along the angle members 2 and 6 are a plurality of horizontally disposed headed metal screws 11 which pass through holes in the overlapping vertical legs of the angle members 2 and 6 and are screwthreaded into metal nuts 12 for clamping the said overlying legs together. One of each pair of holes through which a screw 11 passes is vertically slotted, as designated at 13, whereby the carriage may be adjusted vertically and secured in vertically adjusted position. Vertically disposed metal adjusting screws 14, disposed at intervals along the angle members 6, pass

upwardly through suitable metal angle brackets 15 secured on the upwardly extending legs of the angle members 6 and are screwthreaded through metal nuts 16 above these brackets and abut the under surfaces of the horizontal legs of the angle members 2 for vertically adjusting the same in a convenient manner.

Thus it will be observed that a plurality 10 of horizontally spaced independently vertically adjustable metal devices arranged in two parallel rows extending longitudinally of the carriage or alley are provided for vertically adjusting the carriage and bed 15 variably throughout their extent, so that the bed may be leveled without planing, whatever planing that is necessary, being to remove only local irregularities on the upper or playing surface of the bed.

20 Leather or other suitable material is preferably interposed between the bed 1 and the carriage and between the members forming the carriage and base, as designated at 17, to effect a slight cushion and to reduce the 25 noise resulting from use of the alley. See Figures 2 and 5.

The cross tie members 7 of the base are extended laterally for the support of ball return chutes 18 at the sides of the bed.

30 It will be observed that the construction is such that the structural metal parts may be, as shown, made from stock metal angle bars and fabricated sheet steel with obvious advantage, and it will be further observed 35 that in addition to providing a bed support of desirable characteristics the carriage and base may be taken down and re-erected with resulting economy in moving the alley.

While I have described and shown one 40 form of my invention I do not wish to be limited to the precise details of construction shown, as changes may readily be made without departing from the spirit of my invention, but having thus described my invention, I claim as new and desire to secure 45 by Letters Patent the following.

Claims:

1. In a bowling alley the combination with 50 a bed carriage including metal members extending longitudinally of the carriage and projecting downwardly in spaced relation, a base including metal members extending longitudinally of the carriage and projecting upwardly in spaced relation and overlapping 55 respective of said first mentioned members, and a plurality of independently adjustable metal devices spaced along and associated with said members for supporting the carriage from the base and adapted to permit 60 vertical adjustment of the carriage variably through its extent.

2. In a bowling alley the combination with 65 a bed carriage including parallel metal members extending longitudinally of the carriage and projecting downwardly, a base including

parallel metal members extending longitudinally of the carriage and projecting upwardly in overlapping relation with respective of said first mentioned members, and means including a plurality of horizontally 70 disposed metal screws spaced along said members and passing through the same for supporting the carriage on the base in vertically adjusted position.

3. In a bowling alley the combination 75 with a bed carriage including parallel metal members extending longitudinally of the carriage and projecting downwardly, a base including parallel metal members extending longitudinally of the carriage and projecting 80 upwardly in overlapping relation with respective of said first mentioned members, means including a plurality of horizontally disposed metal clamp screws spaced along 85 said members and passing through the same for securing the carriage on the base in vertically adjusted position, and means including a plurality of vertically disposed metal screws spaced along said members for vertically adjusting said carriage. 90

4. In a bowling alley the combination with 95 a bed carriage including metal members extending longitudinally of the carriage in spaced relation and metal cross tie members secured therewith and extending therebetween at intervals therealong, and a plurality of independently adjustable metal devices spaced along and associated with said longitudinal members for supporting the carriage and adapted to permit vertical adjustment 100 of the carriage variably throughout its extent.

5. In a bowling alley the combination with 105 a bed carriage including a pair of parallel metal angle members extending longitudinally of the carriage and having legs thereof extending downwardly and metal cross tie members secured therewith and extending therebetween at intervals therealong, a base including a pair of parallel metal angle 110 members extending longitudinally of the carriage and having legs thereof extending upwardly in overlapping relation with respective of said first mentioned angle members and metal cross tie members underlying 115 said last mentioned angle members at intervals therealong, and a plurality of independently adjustable metal devices spaced along and associated with the said overlapping legs of said angle members for supporting the carriage from the base and adapted to permit vertical adjustment of the carriage variably throughout its extent. 120

6. In a bowling alley the combination with 125 a bed carriage including a pair of parallel metal angle members extending longitudinally of the carriage and having legs thereof extending downwardly and metal cross tie members secured therewith and extending therebetween at intervals therealong, a base 130

- including a pair of parallel metal angle members extending longitudinally of the carriage and having legs thereof extending upwardly in overlapping relation with respective of said first mentioned angle members and metal cross tie members underlying said last mentioned angle members at intervals therealong, means including a plurality of horizontally disposed metal clamp screws 5 spaced along said angle members and passing through said legs of the same for securing the carriage on the base in vertically adjusted position, and means including a plurality of vertically disposed metal screws 10 associated with and spaced along said angle members for vertically adjusting said carriage.
7. In a bowling alley the combination with a bed carriage including a pair of parallel metal right angle members extending longitudinally of the carriage and having legs thereof extending downwardly, metal angle members secured therewith and extending therebetween at intervals there- 15 along, and metal angle members secured upon the horizontal legs of respective of said first mentioned angle members and extending therealong and projecting above the same for transversely retaining a bed on 20 the carriage, a base, and means associated with the downwardly extending legs of said first mentioned angle members whereby said carriage is carried by the base for vertical adjustment variable throughout the extent 25 of the carriage.
8. In a bowling alley the combination with a bed carriage including a pair of parallel metal right angle members extending longitudinally of the carriage and having legs thereof disposed inwardly and projecting downwardly, metal angle members secured therewith and extending therebetween at intervals therealong, and metal right angle members secured downwardly on respective 30 of the horizontal legs of said first mentioned angle members and having legs thereof disposed inwardly and projecting upwardly for transversely retaining a bed on the carriage, a base including a pair of 35 parallel metal right angle members extending longitudinally of the carriage and having legs thereof extending upwardly in overlapping relation with respective of the 40
- downwardly projecting legs of said first mentioned angle members, and a plurality 55 of independently vertically adjustable metal devices associated with said overlying legs of said first and last mentioned angle members and spaced therealong for supporting the carriage from the base. 60
9. In a bowling alley the combination with a bed carriage including a pair of parallel metal right angle members extending longitudinally of the carriage and having legs thereof extending downwardly, a base including a pair of parallel metal right angle members extending longitudinally of the carriage and having legs thereof extending upwardly in overlapping relation with respective of the downwardly projecting legs of said first mentioned angle members and metal cross tie members of inverted U-shape underlying said last mentioned angle members at intervals there- 65 along and secured therewith, and a plurality of independently vertically adjustable metal devices associated with said overlying legs of said first and second mentioned angle members and spaced therealong for supporting the carriage from the base. 70
10. In a bowling alley the combination with a carriage including a pair of parallel metal right angle members extending longitudinally of the carriage and having legs thereof extending downwardly, a base including a pair of parallel metal right angle members extending longitudinally of the carriage and having legs thereof extending upwardly in overlapping relation with respective of said first mentioned angle mem- 75 bers, metal cross ties of inverted U-shape underlying said last mentioned angle members at intervals therealong and secured therewith, and a pair of parallel metal inverted U-shaped members extending longitudinally of the carriage and underlying said first mentioned U-shaped members, and a plurality of independently vertically 80 adjustable metal devices associated with said overlapping legs of said first and second mentioned angle members and spaced therealong for supporting the carriage from the base. 85
11. In witness whereof I hereunto affix my signature this nineteenth day of April, 1927.
- THEODORE R. TREIBER.
